UNITED STATES PATENT OFFICE.

CHARLES I. WILLIAMS, OF DAYTON, OHIO.

ROTARY ENGINE.

SPECIFICATION forming part of Letters Patent No. 660,675, dated October 30, 1900.

Application filed February 12, 1900. Serial No. 4,917. (No model.)

To all whom it may concern:

Be it known that I, CHARLES I. WILLIAMS, a citizen of the United States, residing at Dayton, in the county of Montgomery and State 5 of Ohio, have invented certain new and useful Improvements in Rotary Engines; and I do declare the following to be a full, clear, and exact description of the invention, such as will enable others skilled in the art to which it app- 10 pertains to make and use the same, reference being had to the accompanying drawings, and to the letters of reference marked thereon, which form a part of this specification.

This invention relates to improvements in 15 rotary engines, and possesses the useful and novel features hereinafter described and claimed.

The object of my invention is to provide a 20 successful rotary engine that may be operated by any of the well-known powers—such as steam, compressed air, gas, or gasoline—and in which the force is applied directly to the piston-wheel at or near the outer circumference.

25 In a detailed description of the invention reference is made to the accompanying drawings, of which—

Figure 1 is a side sectional elevation of my 30 improved rotary engine with the outer casing removed. Fig. 2 is a transverse or vertical section of the same.

In the following specification similar reference-letters indicate corresponding parts in the drawings.

35 A designates the base of the engine, and B is a semicylindrical casing secured thereto, the two forming a chamber in which is mounted a piston-wheel C on shaft D, the position of the shaft, and likewise the axis of the piston-wheel, being eccentric to the center of the chamber. The periphery of the piston-wheel is provided with a series of cams E, the number of which may be varied according to the 40 size of the wheel. These cams control the admission-valve G, which is normally pressed against said cams by means of a coil-spring c. A series of pistons or flanges F are carried on the piston-wheel at points adjacent to the highest parts of the cams. These pistons are 45 bifurcated at their connecting ends to provide two projecting portions, which extend

on each side of the wheel C, and said pistons F are made adjustable in and out from the axis of the wheel by means of set-screws a, such adjustment being necessary in order 55 that the pistons may be in proper contact with the bottom of the air-tight chamber H when passing therethrough. The said air-tight chamber H is formed in the base, but may be formed elsewhere within the casing. As is 60 shown in the drawings, this chamber has adjustable side walls J, which may be adjusted to snugly fit the sides of the pistons by means of set-screws b. This air-tight chamber occupies a portion of the circumference of the 65 piston-wheel and extends from a suitable point above or beyond the inlet-passage e to the exhaust-passage d. The power enters the port f, and when the valve G is in a position with its port i registering with the passage e the power passes into the air-tight chamber H and, coming in contact successively with each of the flanges F, causes a 70 rotation of the cam-wheel and shaft. As the gradually-increasing surface of each of 75 the cams E rides against the inner end of the admission-valve G the power is momentarily shut off from the passage e, during which time the chamber H exhausts through passage d, and as the lower surface of the 80 next following cam approaches the valve G said valve is permitted to move in under the pressure of spring c, at which time the port i therein registers with the passage e. The valve G is held against the cams E at all 85 times by the spring c and forms a wall closing the end of the air-tight chamber H and receives all the back pressure, so that the power is enabled to exert its full force on the pistons to drive the wheel in the direction indicated by the arrows. This feature of the 90 valve forming an inclosing wall for the end of the chamber is an important feature of my invention.

It will be observed that the cams or flanges 95 E and cam-wheel C are only in frictional contact with other parts while they are passing through the air-tight chamber H and that said chamber H approximates only about one-third of the circumference of the cam-wheel. 100 It will therefore be seen that the friction is reduced to a minimum. I have shown the

side walls J of the air-tight chamber H as adjustable. The pistons F may also be made non-adjustable.

Having described my invention, I claim—

- 5 1. In a rotary engine, the combination of a piston-wheel having cams, an inlet-valve controlled by said cams, an air-tight chamber within the casing, and pistons or flanges carried by said piston-wheel and which receive the pressure as they enter said air-tight chamber, said pistons or flanges projecting over the sides of the piston-wheels, and means for adjusting the said pistons or flanges, substantially as specified.
- 15 2. In a rotary engine, the combination with a casing, and an air-tight chamber formed therein, of a piston-wheel, cams on said wheel, an inlet-valve operated by said cams to admit pressure to said air-tight chamber, and 20 pistons or flanges carried by said wheel, said pistons or flanges having extensions which project on each side of the piston-wheel, and the said pistons and wheel adapted to form air-tight inclosures for said chamber and the 25 pistons receiving pressure from the admis-

sion-valve as they enter said chamber and means for adjusting the positions of said pistons or flanges.

3. In a rotary engine, the combination with a casing, of a piston-wheel fitting within said casing closely for a portion of its circumference, and thereby forming an air-tight chamber between the supply and exhaust openings, an inlet-valve discharging into said air-tight chamber and forming a wall for one end 35 of the air-tight chamber, cams on the piston-wheel controlling the position of said valve, and pistons carried on said wheel and receiving pressure as they enter the air-chamber said pistons having bifurcations or extensions which project on each side of the wheel, and means for adjusting said pistons, substantially as described.

In testimony whereof I affix my signature in presence of two witnesses.

CHARLES I. WILLIAMS.
